UNITED STATES PATENT OFFICE.

PHILIP M. SHARPLES AND DAVID TOWNSEND SHARPLES, OF WEST CHESTER, PENNSYLVANIA, ASSIGNEES TO SHARPLES SEPARATOR COMPANY, OF WEST CHESTER, PENNSYLVANIA, A CORPORATION OF PENNSYLVANIA.

CREAM SEPARATOR.

Application filed August 2, 1922. Serial No. 579,200.

This invention relates to centrifugal separators, and more particularly to such a separator of the hand-operated type.

One of the objects of this invention is to provide a separator of relatively small size and comparatively large capacity, which is so constructed and assembled that its parts are of light weight, and the device may be sent through the mails instead of being shipped by freight or express as heretofore; and in particular in that the several parts are so constructed and arranged with respect to each other that dismounting and assembling is quickly and immediately done.

15 A further object of this invention resides in constructing a centrifugal separator wherein the bowl barrel surrounding the rotatable bowl is detachable with the bowl, thus permitting a closer fit and a more compact and lighter arrangement.

20 A further feature of this invention resides in supporting the bowl barrel on the drag bush surrounding the lower nozzle of the rotating bowl whereby the weight of the bowl barrel acts as a drag for the bush.

25 Still a further phase of the invention resides in the means for positioning the bowl barrel about the rotatable bowl with the weight of the barrel freely resting on the bush which centers the bowl, the positioning means being constructed and arranged to prevent the barrel from rising or getting out of alinement.

Another object of the invention resides in 35 providing a novel type of latch for holding the bowl barrel in position, which latch includes means for preventing it from rattling during the high speed rotation of the bowl.

Yet another object of this invention resides 40 in providing a novel means for supporting the supply can in operative position over the feed cup, so that milk or other fluid is properly fed from the supply can to the feed cup and thence to the inlet nozzle of the rotating bowl. This supporting means for the supply can is constructed and arranged to 45 cooperate with the means for positioning the bowl barrel so that the supply can can not be properly placed in operative position until 50 the bowl barrel is locked in its proper place.

Yet another feature of the invention resides in the simple type of valve and operating means therefor whereby the supply of fluid passing from the supply can to the 55 feed cup is conveniently regulated.

A further feature of this invention resides in the simple means for centering the feed cup on the supporting stand, which means is constructed and arranged to also act as a centering means and support for the drag 60 bush for preserving the true alinement of the drag bush which in turn not only supports the guard barrel but also preserves the true alinement of the rotating bowl.

These and other objects will in part be 65 obvious and will in part be hereinafter more fully disclosed.

In the drawings which show by way of illustration one embodiment of the present invention—

70 Figure 1 represents a side view of the device with the feed cup partially broken away;

Fig. 2 is a view at right angles thereto, certain of the parts being broken away to 75 show the interior mechanism;

Fig. 3 is a sectional plan view;

Fig. 4 is a detail view of the feed cup, centering means and drag bush;

Fig. 5 is a collective perspective view of 80 the same, and

Fig. 6 is a detail sectional view of the control valve for the supply can.

Referring now in detail to the drawings, the milk separator comprises a light, durable 85 standard or frame made of sheet steel parts pressed into proper shape by power presses and secured rigidly together. Preferably this frame or standard is composed of four sheet steel stampings, an upper piece or gear case 1, two side pieces 2 and 3, one for each side, and a bottom piece 4. The gear case 1 is preferably made by pressing it into basin form, not only to the end that the usual gearing for driving the bowl spindle, 90 three of which are shown as at 5, 6 and 7 in Fig. 2, can be mounted on suitable spindles 8, 9 and 10, passing from one side of the case to the other, but also that this case will effectively hold the lubricating oil into which 95 the bottoms of the gears dip so as to splash the lubricating oil about as heretofore. By constructing this gear casing of pressed steel in one integral piece rather than making it in two halves attached to the upper end of the side pieces and welded together, all danger of oil leakage from the gear case is 100 obviated. As shown clearly in Fig. 2, the two side pieces are provided at their upper ends with cradle-shaped extensions which, 105 110

when they are united together, form a suitable seat for this upper basin 1, the union being effected by spot welding. The bottom piece 4 of the standard is made in the same way from one piece of metal pressed into basin-form, but inverted. The four pieces including the upper basin 1, the inverted lower basin 4, and the intermediate side pieces 2 and 3 are secured rigidly together to form a light unitary standard of pressed sheet steel. The open top of the upper gear case or basin 1 is adapted to be closed by a suitable frictional cover 11 of any desired design.

15 The large gear 5 in the gear casing 1 intermeshes with the usual worm 12 rigid with the vertically depending bowl spindle 13 which is mounted in a bearing carried in the upper part of the casing. This bearing will 20 be further described in detail. The hanging spindle 13 passes freely through an opening 14 in the bottom portion of the gear casing 1, which construction permits the free and unrestricted rotation of this bowl spindle. The bottom of the bowl spindle is provided with the usual type of bayonet connection 15 with the upper portion 16 of the rotating bowl 17. This bowl is provided with a lower milk feeding inlet 25 or nozzle 18 shown in dotted lines in Fig. 2. Inasmuch as the construction of the bowl per se is not new, no further reference to its detail construction will be made. The bowl barrel or guard barrel 19 surrounding the 30 bowl is made of sheet metal and is detachable, thus permitting a closer fit, smaller size, and lightness in weight, and also permitting the easy removal of the bowl and its parts for cleaning purposes. To this end, the bowl barrel is formed as a cylinder, 35 preferably closed by a flanged end cap 20 having a central opening 21 surrounded by a depending flange 22. This bottom closure 20 is also provided with openings 23 and 40 24 arranged on opposite sides of the central opening 21. The upper end of the cylinder is preferably formed with the lower feed pan 25 integral therewith, which may be accomplished by soldering or otherwise, and 45 just below this integral feed pan 25, the cylinder is provided with a rigid sleeve or collar 26 formed with oppositely projecting locking lugs 27 which are recessed as at 29 to receive the barrel latch hereinafter described. Preferably, the nozzle 30 of the 50 lower receiving pan is supported by means of a brace 31 either welded or soldered to the nozzle 30 and collar 26. By means of the above construction, the integral bowl barrel 55 and lower receiving pan may be removed as a unit. The upper rim 32 of the lower receiving pan is constructed to make a friction fit with the upper receiving pan 33 which is provided with an integral nozzle 34. A 60 detachable cap 35 also makes a friction fit

with the top of the upper receiving pan. The upper and lower receiving pans are provided with suitable apertures so that the revolving bowl spindle 16 and bowl 17 are not in contact therewith. Preferably, the upper receiving pan is provided with an inwardly projecting bottom piece or flange 36 which is provided with an upwardly projecting neck 37 slightly spaced from the spindle 16. This piece 36 constitutes a bottom for the upper receiving pan from which the milk flows out through the nozzle 34 as is well known in the art. It will also be observed that the cap 35 is formed with a central opening 38 spaced from the spindle 75 16 so that there is no interference with the separator bowl and spindle.

80 Means are provided for mounting the feed cup directly on the basin 4 of the standard and for centering the feed cup in its correct position so that the nozzle 18 of the revolving bowl spindle which depends into this feed cup, will be maintained in correct position relative thereto. To this end, the sheet metal base 4 is provided with an insert 39 provided with upstanding lugs 40 preferably constructed as quadrants of a circle, which quadrants are preferably made by slotting the projection 39 in radial directions at right angles. If desired, these projections may be formed by striking up the sheet metal of the base 4.

90 95 The feed cup 41 is provided with cooperating means for centering it on the lugs 40. In the preferred form, the base of the feed cup is provided with an aperture for an insert 42 comprising similarly formed struck-up lugs 43 and cross passages 44, the lugs 43 being struck up from sheet metal and thus being hollow underneath so that they will 100 exactly fit over the lugs 40 of the insert 39. In this manner, the feed cup is held fixedly in position.

105 110 Means is also provided in connection with this centering means for also centering the drag bush, which in turn not only centers the nose 18 of the revolving bowl, but also supports the guard barrel 19. Preferably a sleeve or ferrule 48 is provided to surround the upstanding lugs 43 of the insert 42. This sleeve is formed with notches 49 which are in alinement with the cut-out passages 44, and constitute means for permitting the free flow of milk or other fluid from the feed cup into the central passages 44 and thence to the nozzle 18 of the rotating bowl 115 as will be hereinafter described.

120 125 It is manifest that this ferrule 48 may be either soldered to the base of the feed cup 41 or may fit loosely around the upstanding projections 43, the former construction being more desirable since it provides some means for maintaining the slots 49 in register with the passages 44.

The drag bush 50 will not be described 130

in detail inasmuch as it forms the subject-matter of a separate application issued to D. T. Sharples, February 6, 1923, Patent Number 1,443,967, and which application is assigned to the assignee of this present application. This drag bush 50 is supported on the lugs 43 within the ferrule, and is free to shift laterally within this ferrule. As shown best in Fig. 4, the drag bush is situated between the flange 22 of the guard barrel 19 and the nozzle 18 of the rotatable bowl so that the horizontal inner ledge 22' of the guard barrel rests upon the drag bush thereby supporting the weight of the barrel. It will also be noted that this depending flange 22 on the barrel lies within the ferrule 48. The end of the feed cup opposite that end which contains the centering lugs 43 is enlarged or rounded as at 51 to form a seat for a float 52, which float cooperating with the valved discharge for the supply can, forms a means for maintaining a constant level of milk or fluid in the cup.

The means for positioning the bowl barrel about the rotating bowl and holding it in such position so that the weight of the bowl barrel rests on the drag bush 50, while preventing the bowl barrel from rising, preferably comprises the pivoted latch shown clearly in Fig. 3. In this construction, the upper portion of the standard is provided with a transverse pin 54 to which is pivoted a latch 55 formed in its outer end with a crescent shaped recess 56 adapted to surround a portion of the bowl barrel 19. This latch 55 swings on this horizontal pin 54 from a raised disengaging position to a horizontal locking position, and to accomplish this locking, the outer ends of the crescent shaped latch are provided with downturned lugs 57 which enter into the recesses 29 of the lugs 27 on the sleeve 26. The latch 55 is also provided with a shiftable keeper 58 pivoted at a point 59 so that it will swing from an outer position shown in dotted lines in Fig. 3 to a closed position shown in full lines therein, where it wedges between the lower rim of the lower receiving pan and the upper shoulder of the sleeve 26. Preferably the pivotal connection 59 is loose, the pivotal point thereof being provided with a coiled spring which puts the keeper under tension and eliminates all rattling.

A supply can 53 of rather large capacity is adapted to be suspended from the standard or frame just over the feed cup. The preferred means for holding the can in this position comprises a bracket 53' attached to one side of the standard, which bracket is adapted to engage a handle 53" on the side of the can so that when this looped handle is slipped over the bracket, the can will be suspended in the desired position. As shown in Fig. 3, this bracket 53' is located on the standard at such a point that it is impossible to place the

supply can on the bracket as long as the latch and keeper 58 are swung to outward position shown in dotted lines in this figure. Therefore, unless the bowl barrel is locked, the supply can cannot be positioned. The bottom of the supply can 53 is provided with an opening 60 which receives a valve seat 61 provided with lateral ports 62. The top 63 of this valve seat 61 is provided with a central stud 64 which forms a pivot for the rotary valve 65 nesting within the valve seat. This valve 65 is likewise provided with ports 66 which when the valve is turned properly, register with the ports 62 of the seat thereby permitting milk to flow down through the discharge port 67 which is circular, to receive the projecting conical nose or float 52. The base of the rotatable valve 65 is provided with a flange 68 about which fits a curved handle 69 extending to the side of the can where it is easily operable to an on or off position. In this manner, the flow of milk from the supply can to the feed cup is easily controlled.

In the upper part of Fig. 2 is disclosed a novel bearing for the hanging spindle 13 which while shown is not claimed in this application, since it forms the subject-matter of a separate application about to be filed by David T. Sharples. In the present construction the hanging bowl spindle 13 is mounted for rotation in a bearing comprising a resilient metal cage 70 which is preferably in the form of a cup having slots 71 cut in its sides part way down. The upper rim or periphery of this cup is flanged as at 72 so as to provide a shoulder seating on a corresponding shoulder of a stationary ring 73 carried by suitable fastening screws 74 on the basin 1. By slotting this metal cage all around from its outer end part way down to its other end, great resiliency is provided. The bottom of this cup or cage 70 receives a spherical race 75 for supporting the balls 76 which seat the conical shoulder 77 of the shaft or spindle 13. By means of this construction, it is evident that the ball race and consequently the bowl and revolving parts are supported by a metal spring cage which gives elasticity or resiliency in all directions, either horizontally or vertically, and at all times tends to return the bearing to its normal central position. This bearing is so constructed that in case the bowl sways sidewise, or the bearing itself moves laterally, or in case of faulty construction when the alinement is not accurate, the balls will nevertheless revolve in a circle and in proper position as regards the revolving bowl spindle. This is due to the fact that the plane passing through the center of the balls will always remain at right angles to the axis of the revolving bowl spindle when the axis sways to one side or the other. Manifestly, this results from the fact that the ball race is approximately a section of a sphere.

So also in the upper portion of Fig. 2 is

shown in detail a novel means for preventing the escape of lubricant through the outlet in the gear casing through which the spindle 13 depends. This construction is not claimed herein since it forms the basis of a separate application filed by David T. Sharples.

As before stated, the vertical depending spindle 13 passes freely through the opening 10 in the bottom of the gear case containing the lubricating oil so that the spindle is free and unobstructed in its rotation. However, it is of the utmost importance that no lubricating oil escape through this opening 15 or run down the spindle 13 into the bowl, either when the bowl is running or when it has come to rest. To prevent this, an oil deflector is located at the mouth of the opening and extends concentrically about this 20 spindle upwardly so as to act as a shield and prevent the oil being thrown from the gears on to the revolving spindle at the opening, or out through the opening. In connection with this shield, there is provided additional means for preventing the 25 direct flow of oil down the revolving spindle 13. The preferred form is shown clearly in Fig. 2 of the drawings, wherein the deflector is constructed as a hollow sleeve 78. In cross section, the sleeve may be heart-shaped, the outer upper periphery thereof being curved around the portion of the gear 30 and inwardly to a point slightly spaced from the spindle 13. The base 80 of this sleeve 78 extends inwardly toward the opening 14 and thence upwardly parallel with shaft 13 as at 81, this latter portion constitutes an upstanding flange and forms with the outer portion of the base 80 a 35 pocket 82 which is preferably provided with a drain hole communicating with the gear casing so that any oil collecting in this pocket will drain back into the gear casing. Within this deflector 78 is located the oil 40 shedder 83 which is fixed rigidly to the spindle 13. This oil shedder 83 has an outwardly projecting flange 84, or in lieu thereof, a notch, which flange directs the oil outwardly under centrifugal force as the spindle rotates. The oil is thus thrown into the 45 pocket 82 of the deflector. It is of the utmost importance that the diameter of the opening between the upper rim of the deflector 78 and the spindle 13 be not greater than the diameter of the flange 84 and also 50 that the diameter of the opening between the flange 81 and the spindle 13, be greater than the diameter of the flange 84. This difference is very slight and is just enough for the flange to pass from the opening. This construction permits the flange 84 to 55 pass freely into the deflector when the parts are assembled. It will be noted from this, that a straight line passing through the 60 inner edge of the upper opening to the inner

edge of the lower opening will touch or intersect the revolving flange 84. By means of this construction, it is not possible for oil to pass in a straight line from this device. Nor is it possible for oil to get between and pass through the device. Other constructions are within the contemplation of this invention, for instance, the flange 81 may be a separate piece and may screw into a thread in the base 80 of the deflector, in which case, this flange 81 may extend inwardly to a point within the diameter of the flange 84 but not touching spindle 13. When it is desired to disassemble the device, the flange 81 may be unscrewed and the shedder removed through the opening.

It is obvious that minor changes in the details of construction and the arrangement of the parts may be made without departing from the spirit of the invention as set forth in the appended claims.

Having thus described the invention, what we claim as new and desire to secure by Letters-Patent, is—

1. In a device of the class described, the combination of a rotatable bowl, a drag bush surrounding the free end thereof and a bowl, barrel surrounding the rotatable bowl, and contacting with said bush so as to act as a drag weight for said bush.

2. In a device of the class described, the combination of a rotatable hanging bowl, a drag bush surrounding the lower end of said bowl and a bowl barrel surrounding said rotatable bowl and resting on said drag bush whereby the weight of said bowl barrel acts as a drag weight for said bush.

3. In a centrifugal separator, the combination of a supporting stand, a bowl rotatably mounted thereon, a drag bush surrounding the lower end of said bowl, a bowl barrel surrounding said bowl, means for supporting said barrel with its weight freely resting on said drag bush, said means being constructed and arranged to prevent the rising or lifting of said barrel.

4. In a centrifugal separator, the combination of a supporting stand, a bowl rotatably mounted thereon, a drag bush surrounding the lower portion of said bowl, a bowl barrel surrounding said bowl, means engaging the upper portion of said barrel for centering the same and for holding it from rising, said means being constructed and arranged to permit the weight of said bowl to rest freely on said drag bush.

5. In a centrifugal separator, the combination of a support, a centering hub thereon, a feed cup, means for detachably centering said feed cup on said hub, a bowl barrel, and means for detachably and concentrically centering said bowl barrel with respect to said centered feed cup.

6. In a centrifugal separator, the combination of a frame formed with a centering hub,

a feed cup, means for detachably centering said feed cup on said hub, a ferrule centered about said means and forming with said means, milk feeding passages, a drag bush disposed within the ferrule, a hanging bowl barrel, said barrel having its lower end concentric with said drag bush and supported thereby.

7. In a centrifugal separator, the combination of a supporting frame having upstanding centering lugs, a feed cup having correspondingly shaped struck-up depressions in its bottom interfitting with said lugs to detachably center said feed cup, a ferrule centered on said struck-up depressions, and a bowl barrel carried by said frame and provided with a centering flange on its bottom located within the ferrule of said feed cup, a drag bush within said ferrule and supporting the weight of the bowl barrel.

8. In a centrifugal separator, the combination of a support, a feed cup, a hanging rotatable bowl, means for detachably centering said feed cup in supported position on said frame and for detachably centering said bowl in said feed cup, said centering means providing a feeding milk passage from said feed cup to said bowl.

9. In a centrifugal separator, the combination of a support, a feed cup, a hanging rotatable bowl, a drag bush adapted to sur-

round said rotatable bowl and to support the weight of the bowl barrel, means for detachably centering said feed cup on said support, said means constituting a centering means for the drag bush, and said means constituting a milk feeding passage from the feed cup to the bowl.

10. In a centrifugal separator, the combination of a standard, a rotatable bowl carried thereby, a bowl barrel surrounding said bowl, a latch for locking said bowl barrel in position, a supply can adapted to be operatively positioned on the standard, said latch being constructed and arranged to prevent the proper location of said supply can on said standard until said latch is in locked position.

11. In a centrifugal separator, the combination of a standard, a rotatable bowl carried thereby, a feed cup for said bowl adapted to be positioned on the base of said standard, a supply can having a bottom port adapted to supply said feed cup, a bracket on said standard and cooperative means on said supply can for suspending the same from said standard with its port over said feed cup.

In testimony whereof, we affix our signatures.

PHILIP M. SHARPLES.

DAVID TOWNSEND SHARPLES.
